UNITED STATES PATENT OFFICE.

JOSEPH HOPKINSON, OF DAYTON, OHIO, ASSIGNOR TO THE COMPUTING SCALE COMPANY, OF DAYTON, OHIO, A CORPORATION OF OHIO.

RACK AND PINION DEVICE FOR SCALES.

Application filed February 3, 1920. Serial No. 356,024.

To all whom it may concern:

Be it known that I, JOSEPH HOPKINSON, a citizen of the United States, residing at Dayton, in the county of Montgomery and 5 State of Ohio, have invented certain new and useful Improvements in Rack and Pinion Devices for Scales, of which the following is a full, clear, and exact description.

This invention relates to improvements 10 in scales of the general type shown in the copending application of L. A. Osgood, Serial No. 105,903. In the application referred to, the scale comprises a main lever suitably fulcrumed and having a depending 15 pendulum and also a draft rod extending to a base lever system and imparting the load to the lever. A counter-balancing pendulum is mounted above the beam and is connected thereto in the usual manner. Up- 20 standing from the beam is a member which carries a rack intermeshing with a pinion and driving a weight indicator in the form of a pointer.

The present invention particularly re- 25 lates to an improved rack construction and a supporting and adjusting means therefor. The construction is such that rack and pinion friction is reduced to a minimum, and the adjustment means are of such form that 30 various desired adjustments may be made in the factory.

It is among the objects of the present in- 35 vention to provide for a multiplicity of ad- justments so that in building the scale, con- ditions which affect the intermeshing of the 40 rack and pinion may be met and overcome without undue difficulty. After the main adjustments are made the rack will prop- erly mesh with the pinion and operate with- out friction, but should occasion arise for further adjustments when the scale is in 45 service, these may be made by repairmen not having the skill of long-experienced sealers.

Further objects and advantages will be 50 set forth in the accompanying specification and shown in the drawings in which:—

Fig. 1 shows in elevation a scale having my improved rack supporting and adjust- 55 ing means applied thereto.

Fig. 2 shows an enlarged view of the rack and supporting means therefor.

Fig. 3 is a sectional view taken on line 3—3 of Fig. 2.

Fig. 4 is an end view of the parts shown

in Fig. 2 looking from the left.

Fig. 5 is an end view of the same parts looking from the right.

Figs. 6, 7 and 8 are views similar to Fig. 2 of modifications.

The scale shown in Fig. 1 comprises a main scale beam 10 fulcrumed at 11 and having a depending pendulum 12 below the pivot and a pendulum 13 above the beam and connected thereto by a suitable connec- 60 tion 14. A pointer 15 is arranged to swing over the usual dial, here shown in dotted lines, and this pointer is mounted in the usual manner upon a journaled arbor car- 65 rying a pinion 16. Extending upwardly 70 from the beam is an upstanding arm 17 which adjacent the upper end has a side 75 projecting bracket or extension 18. The usual draft rod 19 extends downwardly from the beam and connects with the base lever system.

My improved rack and supporting and adjusting means therefor will now be de- 80 scribed. The bracket 18 is drilled with a vertical hole 20, the center line of which is 85 substantially in line with the fulcrum 11 of the main beam. Passing through this hole is a threaded stud 21 (see Fig. 4) adapted to be clamped to the bracket by nuts 22. The upper end of the stud is 90 forked as shown at 23—24. One forked portion is drilled to receive a pair of cap 95 bolts 25. The other forked portion is threaded to receive the ends of said bolts. Intermediate the forks 23—24 is a bracket 90 26 (see Fig. 3) which is drilled with holes of greater size than the shank of the cap to permit the cap bolts to pass freely there- 100 through and to allow the bracket to be ad- justed vertically, horizontally or angularly with respect to the forks and the stud. After the desired adjustment is made the bolts are tightened, thereby clamping the bracket securely between the forks. This adjustment will hereafter be termed the radial adjustment.

The upper part of the bracket is hori- 105 zontally drilled to receive a round rod 27. A suitable set screw 28 is provided to clamp the rod in any desired position with respect to the bracket. Suitably fastened to rod 27 is a vertically disposed member 27^a carrying a pin 29 which forms a supporting pivot for a member having fastened thereto an arcuate rack 30. The curvature of this rack 110

is such that the pitch line of the rack practically coincides with the arc of a circle struck from the fulcrum point 11 as a center and tangent to the pitch line of the 5 pinion 16.

A vertical member 31 (see Fig. 3) is slotted and through the slot extends a screw by which the member is fastened to the end of bracket 26. The slot provides for a vertical 10 adjustment of the member 31 with respect to the bracket. The upper end of the vertical member is slotted to receive the arcuate rack 30 and guide the same, thereby preventing excessive side play and twisting of the 15 rack and possible binding when in use. Integral with the vertical member 31 is a shoulder 32 which is drilled and tapped to receive a threaded tube 33 (see Fig. 2). This tube is provided with a shoulder at its 20 forward end and within the tube is a light coil spring 34 which urges a shouldered plunger 35 forwardly in the tube. A suitable plug 36 closes the rear end of the tube and retains the coil spring in position there- 25 in.

The threaded tube is provided with a suitable lock nut 37 for retaining the same in any desired position with respect to the supporting shoulder portion 32 and the 30 lower end of the tube is provided with a knurled head to facilitate the turning of the same with the fingers after the lock nut is loosened. The tube and its threaded socket is slightly inclined from the vertical as best 35 shown in Fig. 2. This inclination is such that the plunger acts radially against the curved rear face of the rack, which face is substantially concentric with the pitch line thereof.

40 It has been found in practice that it is extremely difficult to obtain true pitch line contact between the pinion and rack, either on account of irregularities in the manufacture of the parts or due to the shifting of the 45 fulcrum of the pinion and there is a tendency for undue friction or binding to exist when the scale is in use, whereby the scale accuracy is effected.

In assembling the parts the stud 21 is so 50 secured in with respect to the bracket that the rack 30 is fairly close to the pinion 16. Care is also taken to align the rack properly with the pinion. Thereafter the cap bolts 55 are loosened and a further fine radial adjustment is made so as to closely approximate pitch line contact between the rack and the pinion. The enlarged holes in the bracket 26 permit either the right or left 60 hand side of the rack to be swung up so as to uniformly engage the pinion. Preferably a slight play is left between the rack and pinion which play is later taken up by the vertical tension device which includes parts 33, 34, 35, 36 and 37.

65 Set screw 28 is then loosened and the rack

shifted back or forth until the pinion has turned the pointer to stand over zero or neutral position. This constitutes the zero or neutral adjustment. This same adjustment may be used to tilt the rack, should one side 70 be higher than the other.

The member 31 should be so set that the upper end properly guides the rack laterally but does not form a bearing for the lower 75 face of the rack.

The foregoing adjustments having been made, the vertical tension adjustment device is so manipulated that plunger 35 presses into light contact with lower face of the free end of the rack and holds the same yielding 80 into substantial pitch line contact with the pinion. If it is found that this result is not secured recourse may again be had to the radial adjustment for shifting the position of the rack pivot. If it is found that the spring tension of spring 34 is too great or too light, this may be corrected by shifting the plug 36 out or in with respect to tube 33. Usually it is found that after the radial adjustment is once properly made, the adjustments to the vertical tension device (including the vertical shifting of tube 33 and the adjustment of spring tension of coil spring 34) will in themselves provide ample correction for maintaining free moving conditions of the rack and pinion. The depth of 90 enmeshment may be controlled by shifting tube 33 and any variation from true pitch line action of the rack and pinion will be compensated for by the spring 34. It is of course desirable that the settings be made so as to exert the minimum of tension upon the rack and so that the rocking of the same about its pivot be reduced to the minimum.

100 While I have herein described one sequence of adjustments, it will be understood that the sequence set forth is merely to illustrate the functions of the different adjustments and other sequence may be used if desired.

In certain cases it will be found that the making of one adjustment affects another in which case it is necessary to "cut and try" until the adjustments desired so correlate with another that the rack meshes properly.

115 The construction illustrated in Fig. 6 is similar to the construction previously explained except that the devices for adjusting the vertical tension on the rack are disposed between the rack pivot 29 and the pinion 26.

In addition, the adjustment for the spring tension of the spring 34 consists in a shouldered closure 36^a which is disposed at the upper end of the threaded tube.

120 In Fig. 7 the rack guide 31 supported by bracket 26 is omitted and a rack guide 31^a connected to the dial hub is employed. In place of the vertical tension device previously used a blade spring 39 is employed 125

which presses the rack lightly into contact with the pinion. This construction does not have the screw adjustment for the vertical tension. Any adjustment to be made is 5 affected by bending the blade spring 39.

In Fig. 8 a similar blade spring 40 is employed which bears downwardly upon an extended end of the member which carries the rack.

10 While I have shown my improvements as applied to an arcuate rack to which they are particularly adapted, a straight rack may be used in which the spring 34 would necessarily have to move the rack and cause 15 it to assume proper contact with the pinion.

What I claim is:—

1. In a scale in combination, a scale beam, a driving pinion, an upstanding arm carried thereby and extending adjacent said 20 pointer driving pinion, and means associated with said arm for pivotally supporting an arcuate rack below said pinion and yieldingly enmeshing the same therewith, and means for controlling within predetermined limits the depth of enmeshment of the 25 rack and pinion teeth.

2. In a scale in combination, a scale beam, a driving pinion, an upstanding arm carried thereby and extending adjacent said 30 pointer driving pinion, an arcuate rack and means associated with said arm for pivotally supporting an arcuate rack below said pinion and yieldingly enmeshing the same therewith, said means having provisions to control 35 within predetermined limits the depth of enmeshment of the rack and pinion teeth and also to control the pressure between said teeth.

3. In a scale in combination, a scale beam, 40 a driving pinion, an upstanding arm carried thereby and extending adjacent said driving pinion, an arcuate rack means associated with said arm for pivotally supporting an arcuate rack below said pinion, and means 45 for adjusting the radial position of said rack with respect to said arm, said means being adapted to be set to retain the rack pivot in fixed position after proper adjustment is secured.

50 4. In a scale in combination, a scale beam, a driving pinion an upstanding arm carried thereby and extending adjacent said driving pinion, an arcuate rack means associated with said arm for pivotally supporting an 55 arcuate rack below said pinion, and means for shifting the support for the rack pivot with respect to the arm and for thereafter setting the same to retain the rack pivot in fixed relation with respect to said arm.

60 5. In a scale in combination with a pointer, driving pinion and an arcuate rack of a scale beam having an upstanding arm extending adjacent said pointer driving pinion, means associated with said arm for 65 pivotally supporting an arcuate rack below

said pinion, means for radially adjusting the pivotal support for said rack, means for laterally shifting the rack to set the pointer driving pinion to zero position, and means for adjusting the vertical tension upon the 70 rack.

6. In a scale having in combination a driving pinion, an arm connected to a moving part of the scale, means for driving the pinion from said arm comprising a supporting structure, a rack pivotally supported at one end thereby and having a free end, means for adjusting the position of said pivotal support, and means for supporting the free end of the rack and for adjusting 75 the position of the said end.

7. In a scale having in combination a driving pinion, an arm connected to a moving part of the scale, means for driving the pinion from said arm comprising a supporting structure, a rack pivotally supported at one end thereby and having a free end, means for adjusting the position of said 85 pivotal support, and means for yieldingly pressing the rack into enmeshment with the pinion and for adjusting the amount of said yielding pressure.

8. In a scale having in combination a driving pinion, an arm connected to a moving part of the scale, means for driving the 95 pinion from said arm comprising a supporting structure, a rack pivotally supported at one end thereby and having a free end, means for adjusting the position of said pivotal support, means for yieldingly pressing the rack into enmeshment with the pinion and for adjusting the amount of said 100 yielding pressure, means for supporting the free end of the rack and for adjusting the position of said end, and means carried by 105 said supporting structure for laterally guiding the free end of the rack.

9. In a scale having in combination a driving pinion, an arm connected to a moving part of the scale, means for driving the 110 pinion from said arm comprising a supporting structure, a rack pivotally supported at one end thereby and having a free end, means for adjusting the position of said pivotal support, means for yieldingly pressing the rack into enmeshment with the pinion and for adjusting the amount of said 115 yielding pressure, means for supporting the free end of the rack and for adjusting the position of said end, and means for bodily shifting the rack laterally with respect to the pinion and said arm to obtain a proper zero setting for the scale.

10. In a scale having a driving pinion and a rack horizontally disposed below the same 125 and spring pressed into enmeshment therewith, means for radially adjusting the rack with respect to its support, means for laterally shifting the rack with respect to its support and to said pinion, said means being 130

also adapted to permit the twisting of the rack with respect to the pinion.

11. In a scale having in combination a driving pinion and an arcuate rack horizontally disposed below the same and spring pressed into enmeshment therewith, and means independent of the spring tension for adjusting said rack with respect to said pinion to cause said rack to enmesh therewith with substantially pitch line contact.

12. In a scale having in combination a driving pinion and a arcuate rack horizon-

tally disposed below the same and spring pressed into enmeshment therewith, means independent of the spring tension for adjusting said rack with respect to said pinion to cause said rack to enmesh therewith with substantially pitch line contact, and means for adjusting the spring tension upon the rack to any desired degree of tension.

15 20
In testimony whereof I hereunto affix my signature.

JOSEPH HOPKINSON.
